CONTINUOUS PRESS FOR SOLID MATERIALS CONTAINING LIQUIDS

Paul Alexandre Henri Villez, St-Sauveur-De-Montagut, France

Application May 13, 1929, Serial No. 362,788, and
in France June 2, 1928

1 Claim. (Cl. 100—48)

This invention relates to a continuous press for solid materials containing liquids to extract the greatest amount thereof to obtain materials as dry as possible.

5 It is essentially characterized in that it consists of a machine comprising in combination with two rollers, usually large in diameter and rotating at a relatively slow speed, rollers in which the supporting shafts are stationary and an Archimedean screw press provided with a movable arresting disc.

The object of this press the speed of rotation of which may be varied according to the nature of the material to be treated, is to subject it to 15 a compressive force previous to its entry into the pressure rollers so that its entry is such that no sliding of the rollers on the said material is produced.

The invention will be described with reference 20 to the accompanying drawing.

Fig. 1 shows a curve of the compression exerted in a solid material placed in a cylinder permeable to the liquid contained in the said material.

25 Fig. 2 shows diagrammatically two compression cylinders.

Fig. 3 shows the resultant forces on a point in Fig. 1 acted on by compression.

Fig. 4 shows the curve of the force resulting 30 from the difference of the decompressive force at rest and the horizontal component of the reaction normal to the surface of the rollers, taking into consideration the co-efficient of friction of the rollers on the material.

35 Fig. 5 is an elevation partly in section of the press.

Fig. 6 is a plan of the same partly in horizontal section.

The present invention is based on the putting 40 into practice of the following considerations.

If in a cylinder permeable to liquids a solid material impregnated with a liquid is compressed, the compressive forces will follow a perfectly determined law (which depends to a certain degree 45 on the speed of this compression) and which may be represented by the curve in Fig. 1. Thus for any point M for an initial volume OV the reduced volume Ov is obtained when the pressure exerted reaches a value Op .

50 Considering Fig. 2; two compressing rollers a and a^1 mounted in fixed bearings between which the material passes and if the initial sheet to be compressed has a thickness M_1 , M_1^1 it is possible as shown in the curve Fig. 1 to determine 55 for the section M, M^1 the compressive force which

must be exerted on this sheet to obtain a reduction in volume from M_1 , M_1^1 to M , M^1 .

If this force is designated by F it may be said to be the resultant of the two forces R and C (Fig. 3).

R being the reaction normal to the surface of the rollers.

C being the thrust of compression.

Owing to the rotation of the rollers these latter exert at the surface of the material to be compressed a drawing force ρR , ρ being the coefficient of friction of the metal of the roller on the material being treated.

This force ρR has for a horizontal component a force C^1 which tends to counterbalance the force C . If therefore it is desired that the material shall not slip from the action of the rollers a pressure equal to the difference between force C and force C^1 must be exerted on the surface M , M^1 .

If the forces C , C^1 are studied it will be found that from M_1 to M_2 it varies as shown in the curve Fig. 4 and there is a maximum at M_3 .

If therefore a compression preferably greater than m_1 , M_3 is exerted on the material it will always be forced under the rollers and the material will be drawn forward by these latter without possible sliding.

The maximum m_3 , M_3 is smaller:

1. as the duration of compression (M_1 , M_2) is longer;

2. as the angle α for the point M is smaller.

In other words rollers of large diameter must be used and given a very slow movement of rotation.

The machine, the object of the present invention, is designed to fulfill the above conditions, being formed of two essential and distinct parts consisting respectively in two pressure rollers a and a^1 , stationary supporting shafts o , o^1 , and in a special press formed in three distinct parts as follows:

The body of the press b is formed in its rear end with a feed hopper c and at its forward end with a tapered delivery d , e , d^1 , e^1 which projects up to the nip of the pressure rollers and has the shape of this latter. Lastly, the continuity of the press allows the arresting disc hereafter described to prevent rotation of the material with the screw f hereinafter described and thereby insure longitudinal advancing of the material.

Inside the body b the screw f , which is an Archimedean screw, is arranged having in section the form shown in Fig. 5 that is to say spirals of

circular section forwards and spirals of rectangular section rearwards.

The spirals of the front end of the screw serve to house the sectors of the disc and those of the rear portion are arranged directly below the hopper and allow for obtaining the maximum volume of material and feeding the same to the first named spirals.

The arresting disc *g* is of very thin sheet material of the shape shown in Fig. 5 and given a speed of rotation such that each circular projection is engaged between the forward spirals of the screw *f* thus forming a barrier.

The machine comprises two side members *i* and *i*¹ suitably held together which carry at their forward end, two fixed shafts *j* *j*¹ on which rotate the two pressure rollers *a*, *a*¹ and at the rear end the frame of the press *b* and the several driving shafts of the machine.

20 The drive is received by a pulley *k* mounted on a shaft *l* which is provided with a toothed wheel *m*. This latter gears with a toothed wheel *n* mounted on a shaft *q* and through it a wheel *n*¹ keyed to a shaft *q*¹.

25 On the two shafts *q* and *q*¹ are keyed respectively two pinions *r*, *r*¹ which gear with toothed wheels *s*, *s*¹ mounted on the pressure rollers *a*, *a*¹.

The shaft *q* transmits its movement to bevel wheels *t* which drive a shaft *u* which operates 30 the pressing elements.

On this shaft *u* is keyed a worm *v* gearing with a wheel *w* mounted on a shaft *x* operating the disc *g*.

At its end the shaft *u* carries a wheel *y* which 35 drives an intermediate wheel *z* which gears with a wheel *2* keyed to the screw *f*.

The relation of the number of teeth on the bevel wheels *t* is found by practice.

In varying this relation, for a constant speed 40 of the rollers *a*, *a*¹, the volume of material fed forwardly by the Archimedean screw *f*, is changed and consequently the preliminary compression exerted on the material to be treated.

It is therefore possible to approach as nearly 45 as possible to the theoretical compression value *C* minus *C*¹ because the mechanical yield of an Archimedean screw as a compression apparatus is excessively poor whilst the mechanical yield of compression rollers not slipping on the material to be compressed is very high.

The material received in the hopper *c* is fed

50 by the screw *f* to the pressure rollers *a*, *a*¹ which are rotated by the driving shafts *q*, *q*¹ and *u* and the bevel wheels *t* and *z*.

55 The screw *f* has a trough of larger size at the entry than at the exit of the material for submitting it to a preliminary compression so as to render it homogeneous, and

means for setting into rotation the said compressor rollers and the said transporting screw, the first at a speed less than the latter so that the threads of the transporting screw serve to effect a preliminary compression of the material.

forward by the spirals of the Archimedean screw *f*. The material discharged from the hopper *c* is moved forwardly by the spirals of the Archimedean screw *f* and somewhat compressed thereby, the arresting disc *g* preventing rotation of the material with the screw and hence greatly facilitating its advance and the material is fed between the rollers *a*, *a*¹ and progressively compressed thereby as will be apparent, the liquid being expressed from the material and discharged therefrom so that none of it returns to the compressed mass, and hence the drying of the compressed mass is greatly facilitated.

At the exit from the rollers the pressure is a maximum and may reach 2 to 300 kg per square centimetre.

It may be remarked that owing to the preliminary pressing there are no pockets in the material in which the liquid can collect to be reabsorbed by the solid material after pressing. This feature of the machine allows for obtaining the maximum dryness of the solid material being treated.

While I have herein shown and described a preferred form of my invention, I would have it understood that changes may be made in the form, proportion and construction of the several parts, without departing from the spirit of my invention and within the scope of the appended claim.

What I claim as my invention and desire to protect by Letters Patent is:—

Continuous press for solid materials impregnated with liquid comprising a casing provided with a tubular transporting element and a hopper to supply material to said tubular transporting element, a transporting screw in the said element, a pair of rotating compressor rollers of relatively large diameter separated by a fixed interval, and mounted in fixed bearings and between which the said transporting element is arranged 110 to discharge, the said screw having a trough of larger size at the entry than at the exit of the material for submitting it to a preliminary compression so as to render it homogeneous, and means for setting into rotation the said compressor rollers and the said transporting screw, the first at a speed less than the latter so that the threads of the transporting screw serve to effect a preliminary compression of the material.
